UNITED STATES PATENT OFFICE

2,525,865

SAFETY MEANS FOR TREADLE OPERATED MACHINERY

Howard T. Chisolm and James A. Harris,
Meridian, Miss.

Application May 17, 1946, Serial No. 670,638

3 Claims. (Cl. 74—526)

1

This invention relates to improvements in safety appliances, especially adapted for use in conjunction with treadle operated machinery.

Heretofore, machine operators, especially those running shirt creasing machines and other foot treadle controlled machine have been subject to the jeopardy of personal injury, due to the likelihood of accidentally catching a hand in the pressing apparatus, or burning himself due to accidental or haphazard operation of the machine.

The present invention contemplates the provision of means which prevents the accidental operation of the treadle controlled machine, except when both hands of the operator are in a safe position.

A very important object of the invention is to provide hand release knobs, operating detent means for the usual treadle, which necessitates the use of both hands of the operator for removing the detent means from a blocking position with respect to the treadle, before the treadle can be operated.

These and other objects and advantages of the invention will become apparent to the reader of the following description.

In the drawings—

Figure 1 is a fragmentary vertical sectional view through a work table, showing the safety appliance in front elevation.

Figure 2 is an enlarged fragmentary detailed sectional view through the spring and knob means;

Figure 3 is a fragmentary vertical sectional view through the detent means;

Figure 4 is a horizontal sectional view taken substantially on line 4—4 of Figure 3;

Figure 5 is a fragmentary vertical sectional view taken on line 5—5 of Figure 3;

Figure 6 is an end elevational view of the treadle base and detent means with the near connecting rod removed.

Referring to the drawings, reference character A denotes the work table of a pressing machine, such as a shirt creasing machine, while reference character B denotes a treadle for operating this type of machine, the same having the usual operating element C extending therefrom.

As is apparent in Figures 1 and 3, a base 5 is provided at its ends with upstanding pairs of ears 6, 6 and between each pair of ears 6, 6 a detent block 7 is pivotally mounted, the same being fulcrumed on a corresponding pin 8, at its lower innermost corner.

Each block 7 is cut away at its upper innermost

corner, as at 9, to define a shoulder 10, forming an abutment for the treadle B, when the treadle B is not being safely operated.

Figure 3 shows that the outer edge of the block 7 has a pair of threaded openings 11 for receiving machine screws 12, serving to attach an angular bracket 13 to this edge of the detent block 7. The bracket 13 is of L-shape with its foot portion disposed outwardly and twisted as at 14. The twisted portion is formed with an opening to receive the lower lateral portion 15 of a connecting rod section 16 and a cotter pin may be employed for preventing displacement of these parts.

The connecting rod sections 16 extend upwardly and interlap the lower inwardly offset portions 17 of connecting rods 18, and collars 19 embrace these overlapping parts and through the medium of a set screw 20, these interlapping parts are firmly clamped together.

The upper ends of the connecting rod sections 18 are connected by eyes 21 to eyes 22 at the lower ends of plunger rods 23, which as is shown in Figure 2, extend upwardly entirely through barrels 24, which depend from the bottom of the work table A in suitable spaced relation with respect to each other.

The lower end of each barrel 24 has an attached cap 25, apertured to receive the corresponding plunger rod 23, while an intermediate portion of each plunger rod 23 carries a washer 26, held in place by cross pin 27 and between which and the cap 25, a coiled compression spring 28 is interposed. The purpose of the spring 28 is to hold the rod sections 16 and 18 elevated in order that the detent blocks 7 will be disposed inwardly to treadle blocking position.

Each of the barrels 24 has a reduced neck extension 29 secured in a corresponding opening of the work table A and through this neck 29 the upper portion of the corresponding plunger rod 23 is snugly slidable.

The upper end of each plunger rod is reduced and threaded as at 30 for disposition into a corresponding hand knob 31.

Between the cap 25 of each barrel 24 and the eye 22 of the corresponding plunger rod 23 is a cushion washer 32, which is capable of absorbing shock when it strikes the cap 25.

In the operation of this appliance, the operator, in order to free the pedal B, must necessarily push downwardly on each knob 31, simultaneously and in order to swing the detent blocks 7 outwardly to the position shown in Figure 3, this against the force and effect of the springs 28. In

other words, his hands must be occupied in effecting release of the detent means, before his foot can operate the treadle to put the machine in operation, and thus maintaining both hands occupied, there can be no haphazard or accidental operation of the treadle, such as might cause injury to the operator, should his hand or hands be in a dangerous position with respect to the pressing element.

As is apparent in Figure 3, the base 5 may have 10 openings therein for receiving anchoring bolts or other securing elements.

While the foregoing description sets forth the invention in specific terms, it is to be understood that numerous changes in the shape, size and materials may be resorted to without departing from the spirit and scope of the invention as claimed hereinafter.

Having described the invention what is claimed as new is:

1. In the machine of the character described comprising an operator's table, a treadle for controlling the machine, a pair of swingable detents for normally holding the treadle against accidental operation, a pair of elongated rod lines 25 extending from the table and operatively connected to said detents, guide tubes projecting from the table and through which the rod lines operate, each of said rod lines being provided with an abutment, located within the corresponding 30 tube and a compression spring on each rod line interposed between the bottom of the corresponding tube and the adjacent abutment.

2. In the machine of the character described comprising an operator's table, a treadle for controlling the machine, a pair of swingable detents for normally holding the treadle against accidental operation, a pair of elongated rod lines 35 extending from the table and operatively connected to said detents, guide tubes projecting from the 40 table and through which the rod lines operate,

each of said rod lines being provided with an abutment, located within the corresponding tube and a compression spring on each rod line interposed between the bottom of the corresponding tube and the adjacent abutment, said rod lines extending above said table and provided with handles at their upper ends.

3. In the machine of the character described comprising an operator's table, a treadle for controlling the machine, a pair of swingable detents for normally holding the treadle against accidental operation, a pair of elongated rod lines 15 extending from the table and operatively connected to said detents, guide tubes projecting from the table and through which the rod lines operate, each of said rod lines being provided with an abutment, located within the corresponding tube and a compression spring on each rod line interposed between the bottom of the corresponding 20 tube and the adjacent abutment, said rod lines being divided into sections and means for adjustably connecting of the sections together to determine the throw of said lines.

HOWARD T. CHISOLM.
